UNITED STATES PATENT OFFICE

90,428

DESIGN FOR A NUT CRACKER

Christian Swensen, of Duluth, Minn.

Application May 5, 1933. Serial No. 48,017

Term of patent 3½ years

To all whom it may concern:

Be it known that I, CHRISTIAN SWENSEN, a citizen of the United States, residing at Duluth, in the county of St. Louis and State of Minnesota, have invented a new, original, and ornamental Design for a Nut Cracker, of which the following is a specification, reference being had to the accompanying drawing, forming part thereof,

I claim:

The ornamental design for a nut cracker as shown.

CHRISTIAN SWENSEN.
